TURBINE DRIVE MECHANISM FOR
HIGH-VACUUM STILLS

Kenneth C. D. Hickman, Rochester, N. Y., assignor to Distillation Products, Inc., Rochester, N. Y., a corporation of Delaware

Application March 2, 1945, Serial No. 580,574

4 Claims. (Cl. 202—205)

1

This invention relates to improved vacuum process and apparatus wherein an element is actuated while in a high vacuum.

Rotation or actuation of an element under high-vacuum conditions presents many difficult problems. It is known, for instance, to rotate elements by use of an electric motor, the armature being exposed to the high vacuum while the field is outside the evacuated receptacle, the wall of the receptacle being positioned between the armature and the field. While this construction is satisfactory for small loads and small sizes of apparatus, considerable trouble is experienced from heating of the armature under heavy duty conditions. The most practical way hitherto available of rotating a member in a vacuum has been through the use of a packed gland, the rotating shaft passing through the gland into the evacuated system and being exposed on one side to the atmosphere and on the other side to the vacuum. Such an arrangement when properly maintained works satisfactorily but occasions arise when gases leak through the gland and spoil the vacuum. Tightening of the gland to minimize the leakage results in overheating and undue frictional losses.

The invention has for its object to overcome the foregoing difficulties and to provide concurrent advantages and simplification of construction not obtainable by other means. Another object is to provide improved process and apparatus wherein an element is rotated or otherwise actuated in the presence of a high vacuum without leakage of the atmosphere into the vacuum. Another object is to provide an improved centrifugal vacuum still. Another object is to improve the state of the art. Other objects are apparent from the following description and claims.

These and other objects are accomplished by my invention which includes vacuum apparatus and process wherein a moving element is actuated in a closed evacuated receptacle by a driving means which is actuated by a low vapor pressure fluid, the driving means having a drive shaft and packed gland and being associated with the closed receptacle so that its drive shaft and packed gland are exposed on one side of the gland to the high vacuum in the closed receptacle and on the other side of the gland to the low vapor pressure actuating liquid in the driving means.

In the following description I have given several of the preferred embodiments of my invention but it is to be understood that these are set forth by way of illustration and not in limitation thereof.

2

In the accompanying drawings, wherein like numbers refer to like parts:

Fig. 1 is a vertical section of vacuum apparatus having a rotatable element positioned therein which is driven in accordance with the principles of my invention;

Fig. 2 is an elevation, partly in section, of a modification of the apparatus illustrated in Fig. 1 and showing the driving mechanism entirely positioned in the evacuated receptacle;

Fig. 3 is a vertical section of a vacuum still having a vaporizing surface rotated in accordance with my invention and;

Fig. 4 is a horizontal section taken on line 4—4 of Fig. 3.

Referring to Fig. 1, numeral 10 designates a cylindrical casing provided with an integral bell shaped end 12 and with a removable bell shaped cover 14 which makes gas-tight connection with casing 10 at flange 16. Numeral 18 indicates a conduit through which the receptacle, or casing 10, is evacuated.

Numeral 20 designates a turbine driving means positioned on shaft 22 which is provided with a packed gland 24. Numeral 26 designates a conduit through which a low vapor pressure actuating liquid is delivered to turbine 20 and numeral 28 designates a conduit through which spent actuating, low vapor pressure liquid is removed from turbine 20. Numeral 30 designates an element to be actuated or rotated in the evacuated chamber.

In operating the apparatus illustrated in Fig. 1 the receptacle 10 is evacuated by high vacuum pumps (not shown) connected to conduit 18. Shaft 22 and rotatable element 30 are caused to rotate by delivery of a low vapor pressure actuating liquid to conduit 26, this liquid being supplied under high pressure and caused to impinge against the buckets of the turbine 20. Spent low vapor pressure actuating liquid is removed through conduit 28. Shaft 22 is exposed on one side to the low vapor pressure actuating liquid in turbine 20 and is, therefore, not exposed to the atmosphere. The other side of packed gland 24 is exposed to the high vacuum. However, since only low vapor pressure liquid is present on the opposite side of the shaft, no leakage can take place except for the small amount of low vapor pressure liquid which itself acts as a lubricant. It is, therefore, unnecessary to tighten gland 24 as tightly as would be required to prevent leakage of gases. The low vapor pressure liquid has no harmful effect on the pressure existing in the evacuated receptacle so that leakage of small amounts of this liquid is not particularly undesir-

able. If excessive leakage of liquid takes place a suitable catchment gutter can be provided.

Referring to Fig. 2, numeral 32 designates a driving means actuated by a low vapor pressure liquid supplied thereto under relatively high pressure through conduit 26. This driving means is positioned entirely within the receptacle 10, the drive shaft 22 passing through the packed gland 24. The operation of the apparatus of Fig. 2 is identical with that described in connection with Fig. 1, the purpose of this illustration being mainly to show the different positioning of the driving means.

Referring to Figs. 3 and 4, numeral 50 designates a cylindrical steel casing provided with an integral base 52 and a moveable cover 54 which makes gas-tight connection therewith at flange 56. Numeral 57 designates an evacuating conduit for removing gases from the closed system which is formed by casing 50, base 52 and cover 54. Numeral 56 indicates a rigid support for an oil actuated gear pump 58, the drive shaft 60 of which passes through packed gland 62 and supports rotatable vaporizing surface 64. Numerals 66 and 68 designate annular gutters mounted upon the inside wall of casing 50, gutter 66 serving to collect condensate draining from the inside wall of 54 and gutter 68 serving to collect undistilled residue thrown from the periphery of rotating plate 64. Liquid collecting in gutters 66 and 68 is respectively withdrawn through conduits 70 and 72. Numeral 74 designates a radiant heater provided with a reflector 76 which serves to heat vaporizing plate 64 to distillation temperature. Gear pump 58 is actuated by a low vapor pressure liquid under high pressure which is delivered from the exhaust side of pump 78 into conduit 80. This liquid flows through a control valve 82, thence into conduit 84 and then flows into gear pump 58, causing rotation of shaft 60 and vaporizing plate 64. Spent impelling liquid then flows into exhaust conduit 86, control valve 88 and thence into the intake 90 of pump 78.

In the equipment illustrated in Figs. 3 and 4, the low vapor pressure liquid is the distilland which is being distilled on vaporizing plate 64. This distilland is introduced at a slow rate through conduit 92 and control valve 94 into the intake side 90 of pressure pump 78. Most of the distilland is continuously recirculated through the circuit formed by conduits 80 and 84, driving gear pump 58, conduit 86 and valve 88. A small part of the distilland is withdrawn from this circuit through conduit 96, the amount being controlled by valve 98 and diaphragm valve 100. This controlled constant volume of withdrawn distilland then flows through conduit 102 and is introduced into the center depression 104 of vaporizing plate 64. This introduced portion is then thrown by centrifugal force in a thin film over the vaporizing plate 64. Vapors are thus generated, pass upwardly and are condensed on the inside wall of cover 54. The condensed liquid then flows by gravity into gutter 66 and is withdrawn through conduit 70. Undistilled residue is thrown into gutter 68 and withdrawn through conduit 72, as previously explained.

The gear pump shown in Figs. 3 and 4 may be one which is ordinarily used to pump oil under relatively high pressure. By supplying the oil to the pump in reverse direction and under high pressure, the pump can be used as a motor. Hydraulic motors especially designed for this purpose can also be used. In the modification shown in Figs. 3 and 4 the distilland may, for

instance, be a fish liver oil. The oil is supplied to pump 58 to cause it to be actuated and small amounts of the fish liver oil are withdrawn and continuously distilled on plate 64. Vitamins contained in the fish oil are thus vaporized and are condensed on the inside wall of 54 and are removed as a concentrate through conduit 70. It is known to use a hot, low vapor pressure fluid to heat the vaporizing surface of a vacuum still. See, for instance, my United States Patent 2,210,927, August 13, 1940. The heat transfer liquid in such a case can be used to actuate the drive for the rotor before it is applied to the surface for heating. The same expedient may be used in connection with cooling fluids supplied to the condensing surface; see, for instance, my patent above referred to.

An outstanding feature of the invention described herein is that leakage of gases is entirely prevented without involving the friction losses heretofore encountered. The low vapor pressure liquid, which may be of any type, such as a hydrocarbon fraction, rotary pump oil, butyl phthalate, etc., not only does not harm the vacuum when small amounts leak into the chamber, but also acts as an efficient lubricant. Other fluids, such as steam, water, air, etc., will not serve as satisfactory actuating fluids.

What I claim is:

1. Vacuum apparatus comprising in combination a rotatable element positioned in a closed receptacle, means for evacuating the closed receptacle, a turbine driving means for driving the rotatable element, a body of fluid of vapor pressure comparable to the vapor pressure of butyl phthalate for actuating the turbine, said turbine having a drive shaft and packed gland and being associated with the closed receptacle so that its drive shaft and packed gland are exposed on one side of the packed gland to the high vacuum in the closed receptacle and on the other side of the packed gland to the actuating liquid in the driving means and means for supplying the driving liquid under high pressure to the turbine.

2. Vacuum apparatus comprising in combination wall means defining a closed receptacle, means for evacuating said receptacle, rotatable evaporating means in said receptacle, turbine driving means for rotating said evaporating means, and means for supplying under high pressure to said turbine driving means driving liquid having a vapor pressure comparable to the vapor pressure of butyl phthalate, said turbine driving means comprising a turbine including a turbine drive shaft, said drive shaft being connected to said evaporating means, and turbine housing means enclosing said turbine and including packed gland means about said shaft, said gland means being exposed on one side to vacuum in said receptacle and on the other side to driving fluid in said housing means.

3. Vacuum apparatus comprising in combination wall means defining a closed receptacle, means for evacuating said receptacle, a rotatable evaporator in said receptacle, turbine driving means for rotating said evaporator, and means for supplying to said turbine driving means, under high pressure, driving liquid having a vapor pressure comparable to the vapor pressure of butyl phthalate, said means supplying driving liquid comprising liquid pumping means and conduit means connecting said pumping means with said turbine driving means, said turbine driving means comprising a turbine including a turbine drive shaft, said drive shaft being connected to said

evaporator, and turbine housing means enclosing said turbine and including a packed gland about said shaft communicating said turbine housing means with said receptacle, said packed gland being exposed on one side to vacuum in said receptacle and on the other side of said gland to driving liquid in said turbine housing means.

4. Vacuum apparatus comprising in combination wall means defining a closed receptacle, means for evacuating said receptacle, a rotatable evaporator in said receptacle, turbine driving means positioned entirely within said receptacle, and means for supplying to said turbine driving means, under high pressure, driving liquid having a vapor pressure comparable to the vapor pressure of butyl phthalate, said turbine driving means comprising a turbine including a turbine drive shaft, said drive shaft being connected to said evaporator, and turbine housing means including a packed gland about said drive shaft, said packed gland being exposed on one side of

said gland to vacuum in said chamber and on the other side of said gland to driving liquid in said housing, said means for supplying driving liquid to said turbine driving means comprising liquid pumping means outside said chamber and conduit means extending into said receptacle through said wall means and communicating with said turbine housing means.
